UNITED STATES PATENT OFFICE

JOHN J. GREENWOOD, OF PHOEBUS, VIRGINIA.

ATTACHMENT FOR CORNETS AND THE LIKE.

1,045,700.

Specification of Letters Patent.

Patented Nov. 26, 1912.

Application filed March 13, 1912. Serial No. 683,559.

To all whom it may concern:

Be it known that I, JOHN J. GREENWOOD, a citizen of the United States, residing at Phoebus, in the county of Elizabeth City 5 and State of Virginia, have invented certain new and useful Improvements in Attachments for Cornets and the Like, of which the following is a specification.

This invention relates to certain improvements in and relating to attachments for cornets, or other musical instruments, and more particularly relates to an attachment for producing French horn tones or effects from cornets or the like musical instruments; and the objects and nature of the invention will be readily understood by those skilled in the art in the light of the following explanation of the accompanying illustration of what I now believe to be the 20 preferred embodiment from among other formations, arrangements and constructions within the spirit and scope of my invention.

An object of the invention is to provide a comparatively simple, inexpensive attachment, that can be quickly applied to or removed from the bell of a cornet or other wind instrument even while the instrument is in use and without the loss of a note, and that will change the tone of the cornet or 30 like instrument into the tone of a different instrument without merely subduing or muffling the cornet tone; for instance, will efficiently change the cornet tone into a French horn tone, and thereby enable a cornet to be instantaneously converted into a French horn or from a French horn back to a cornet, by merely application of the attachment to the cornet or by removal thereof from the cornet while the cornet is being 40 used.

A further object of the invention is to provide an attachment for a cornet, or the like, whereby such instrument can be utilized for producing French horn tones or 45 effects and to play the French horn part in orchestra or solo renditions.

The invention consists in certain novel features in construction and in combinations and arrangements as more fully and particularly set forth hereinafter.

Referring to the accompanying drawings;—Figure 1, is a sectional view showing the attachment applied to the bell or mouth of a cornet; or other wind instrument to 55 which it might be adapted. Fig. 2, is a view

showing the attachment reversed and nested in the cornet bell for packing, transportation, or carrying in a bag or satchel. Figs. 3, 4 and 5, are detail and perspective views.

The attachment consists of a bell-like or flaring hollow shell 1, open at its front and rear ends, and longitudinally open from front to rear except for certain transversely arranged obstructions. The shell has a reduced forwardly projecting front end terminating in the comparatively small central outlet opening 10. The shell flares and enlarges rearwardly so that the diameter of its rear end is approximately equal to that of the front end of the bell or mouth 2, of a cornet (or other instrument) for which the attachment is adapted. The shell is provided with means whereby it can be quickly and readily applied to and removed from the bell of a cornet even while the cornet is in use and without the loss of a note. This quick action is desirable in those instances where a cornet is to play the parts of both the French horn and the cornet, and the change from one to the other must be almost instantaneous.

In use, the rear edge of the large end or bell of the attachment fits or rests against the front edge of the cornet bell and the attachment is arranged exteriorly thereof and projects and tapers forwardly therefrom in virtual direct forward reducing continuation of the cornet. As a means whereby the attachment can be coupled to the cornet bell, I provide the upper part of the rear edge portion of the attachment shell with one or more, usually two, downwardly and rearwardly projecting hooks or hangers 12, spaced a distance apart and fixed to the shell and usually each provided with a cushioning lining. The arrangement of these hooks or hangers is such that the attachment can be moved down to proper position at the front of the cornet bell with the hooks 12, fitting over the top portion of the cornet bell and supporting or hanging the attachment in proper position on the bell with the lower portion of the rear edge of the attachment bearing against the lower portion of the front of the cornet 11. The attachment can be quickly lifted from the cornet and as quickly dropped to position on the cornet bell by one hand of the cornetist while the instrument is in use performing its part.

The attachment is so formed at the lower

portion of its rear or flared end as to provide a reduced outlet, vent, or relief opening from the lower portion of the chamber formed by and within the bell of the cornet 5 and the rear end of the attachment. For instance, I show the lower portion of the rear edge of the attachment shell formed with a notch or cutaway portion 11, to form such air outlet or vent.

16 The attachment shell is interiorly closed, except for a reduced longitudinal side passage 14, by a transverse partition or diaphragm for the purpose of forming a sound chamber in the bell of the cornet and rear 15 end of the attachment shell, closed except for the reduced lateral vent or relief opening 11, and the reduced longitudinal air passage 14, usually arranged at the same side of the shell as vent 11.

20 To convert the cornet tones delivered into said chamber, into the full or deep French horn tones for issuance from said chamber through the vent 11, and passage 14, I provide said chamber with a so-called padded 25 wall against which the sound waves from the cornet are directly delivered. To this end I show the hereinbefore mentioned transverse partition composed of an imperforate wall or diaphragm 16, of so-called 30 padding arranged behind and supported by a thin perforated metal plate 13. I usually employ a thin brass plate 13, having a number of transverse perforations 15, uniformly distributed throughout the same and exposing 35 the padding 16, behind the perforations, I have attained advantageous results where the padding is formed by superimposed sheets one or more of which are of somewhat porous cushioning material. For instance, I can face the rear side of the plate 13, with a sheet of fabric caused to adhere to the surface of the plate. For instance, adhesive cloth or fabric might be used for this purpose. One or more layers of sheet 40 cotton can be then placed over said secured sheet of fabric and backed by a sheet of paper or the like properly glued or secured to maintain the sheet cotton in place and to form the front surface of the padded wall.

45 The passage 14, can be formed by notching the edge portion of the partition formed by the plate 13, and padding 16, and in the specific example illustrated, this passage 14, is arranged immediately in advance of the 50 vent 11, and is formed by a curved cut away portion in the lower edge of the partition. 55

In rear of the reduced front end or nose of the attachment shell and immediately in front of but spaced from the passage 14, 60 through partition 13, I provide the shell with an internal fixed transverse narrow baffle plate or wall 17, having a central transverse perforation or sound passage 18. This transverse plate is arranged across the interior of the shell so as to divide the longitudinal

sound passage by providing comparatively narrow passages between the edges and walls of the shell.

The top of the shell intermediate the front and rear ends of the shell and in rear 70 of the plate 13, is provided with a suitable lateral escape or outlet preferably formed by a group of adjacent approximately uniformly spaced or arranged transverse perforations 19.

75 The baffle plate 17, is of peculiar advantage in serving as a check in preventing so-called split or jar of the tone of the instrument should the instrument be over-blown in rendering a fortissimo passage.

80 Furthermore, this baffle plate is of advantage as an aid in the production of equal tones.

85 The formation and internal arrangement of the shell are such as to most efficiently convert or transform the cornet tones into the French horn tone, every note perfect in tune from lower to upper register and viceversa. The attachment does not mute or subdue the cornet tone but produces the 90 French horn effect, as though the performer laid aside the cornet and took up and performed on the French horn.

95 The attachment shell approximates the shape of the cornet bell, and hence the attachment, when detached from the cornet can be reversed and inserted or nested in the cornet bell, when the instrument is to be placed in its case or satchel for packing or transportation.

100 It is evident that various changes, variations and modifications might be resorted to without departing from the spirit and scope of the invention and hence I do not wish to limit myself to the exact disclosure hereof.

105

What I claim is:—

1. An attachment for cornets, and the like, consisting of a bell-shaped shell having the edge portion of its large end notched, and having series of side perforations in its 110 front portion, and internal obstructions within the shell.

2. An attachment for cornets and the like, consisting of a hollow shell tapering forwardly from an enlarged open receiving end to a front reduced open end, and having a side opening at its large end and side perforations through its reduced forward portion, a padded partition spanning the interior of the large end of the shell and having 115 a passage through one edge portion, said partition inclined forwardly to said passage, and a transverse partition within the shell in rear of said passage and having an opening therethrough and passages past its longitudinal edges.

120 3. A "French horn" attachment for cornets, and the like, consisting of a hollow shell adapted to be removably hung on a cornet bell and project forwardly therefrom,

125

130

said shell having a reduced front end opening, and formed with side outlets, and a partition extending across the interior of said shell and composed of a thin perforated metal plate and padding facing said plate and extending across the perforations therethrough.

4. A "French horn" attachment for cornets and the like, consisting of a hollow shell tapering forwardly to a reduced front end opening and at its rear end having a notch forming a side outlet, and partitions within said shell.

5. A "French horn" attachment for cornets and the like, consisting of a hollow shell having a rear end opening and tapering forwardly to a reduced end opening, and a partition within said shell having a passage therethrough, said partition being composed of a thin perforated metal plate faced by padding closing said perforations.

6. A "French horn" attachment for cornets and the like consisting of a forwardly tapering casing adapted to be reversed and nested in the cornet bell for packing, said casing at its enlarged rear end being provided with a pair of exterior spaced hooks

located at the upper portion of said end and adapted to exteriorly engage the cornet bell and permit the casing to be quickly lifted therefrom or placed thereon with its rear edge held to the front edge of the cornet bell, said casing having front and rear openings and an interrupted sound passage therethrough.

7. A "French horn" attachment for cornets, and the like, consisting of a forwardly tapering casing provided with means for removably applying the same to a cornet bell, said casing having front and rear end openings, and side outlets at its large rear end and reduced front portion, a padded partition spanning the interior of the large end of the casing and a partition within the front portion of the shell in rear of said front end opening for the purposes substantially as described.

In testimony whereof I affix my signature in presence of two witnesses.

JOHN J. GREENWOOD.
